Primary Examiner — Elizabeth J Oswecki(74) *Attorney, Agent, or Firm* — Wilson Sonsini Goodrich & Rosati(57) **CLAIM**

The ornamental design for a multispace parking pay station, as shown and described.

DESCRIPTION

FIG. 1 is a front elevational view of a multispace parking pay station, showing our new design;

FIG. 2 is a right side elevational view thereof;

FIG. 3 is a left side elevational view thereof;

FIG. 4 is a rear elevational view thereof;

FIG. 5 is a top plan view thereof;

FIG. 6 is a bottom plan view thereof; and,

FIG. 7 is a top front perspective view thereof.

The broken lines shown in the drawings represent portions of the multispace parking pay station that form no part of the claimed design.

1 Claim, 3 Drawing Sheets# US D795,523 S
